REACTION MEANS FOR ROTATING AMMUNITION PROJECTILES AT LOW SPEEDS

William J. Kroeger, Philadelphia, Pa., assignor to the United States of America as represented by the Secretary of the Army

Application February 28, 1952, Serial No. 274,044

1 Claim. (Cl. 102—51)

(Granted under Title 35, U. S. Code (1952), sec. 266)

The invention described herein may be manufactured and used by or for the Government for governmental purposes without the payment of any royalty thereon.

Recent developments in the military weapon and ammunition art have led to the use of what has been termed the "shaped charge." This type of projectile, among others, requires a very minimum amount of spin while in flight, as too much spin has been known to spoil its armor-piercing or other such desired characteristics. On the other hand, some small amount of spin is necessary in order to offset the normal lack of symmetry in the manufactured parts, and more fully discussed in application Serial No. 224,435, filed May 3, 1951 (now abandoned). In the case of the gun and ammunition herein illustrated (Fig. 1), a recoilless firing device similar to that shown by Kroeger-Musser U. S. Patents 2,466,714 and 2,472,111 but employing a more recent type of projectile which is fin stabilized, it has been determined that a suitable compromise between these two requirements is on the order of 10-20 revolutions per second (R. P. S.). Prior to my invention, the conventional means for causing projectiles to rotate, e. g. mechanical engagement between a rotating band and a rifled gun bore, caused rotation at a speed which far exceeded these relatively low speeds.

Broadly stated, therefore, it is the principal object of my invention to provide a means for imparting a controlled, low rotative speed to projectiles fired from a rifled or smooth bore gun.

Another object is to accomplish such means in a fast, economical manner with a minimum amount of alteration being required for the ammunition and none for the gun.

These and other related objects are accomplished by my invention as will be seen by reference to the following specification and the annexed drawings, wherein:

Fig. 1 shows portions of a barrel and breech, in longitudinal section, of a rifled recoilless gun, together with a plan view of an ammunition round whose projectile's bourrelet portion is provided with a series of reaction engines, in the form of specially designed nozzles, to effect a low speed in accordance with my invention;

Fig. 2 is view similar to Fig. 1 except that the rearward part of the ammunition round's cartridge case has been eliminated, and the reaction engines are each comprised of a reservoir and a nozzle;

Fig. 3 depicts an enlarged portion of the reaction engine's nozzles and the opposed wall of the smooth bore gun barrel as seen from line 3—3 of Fig. 1;

Fig. 3A is an illustration identical with that of Fig. 3 except that the bore of the gun barrel bears rifling lands and grooves such as are shown in Fig. 2; and

Fig. 4 is a much enlarged showing of the reaction engine portion (as shown in Fig. 2) on which has been super-imposed the lands of a rifled gun barrel just as if the view was through the gun's rear wall.

From the drawings and the following description it will be noted that I have accomplished the aforementioned objects by uniquely providing in the projectile's bour-

2

relet portion reaction engines consisting of nozzles, sometimes supplemented with reservoirs, which preferably are broached in the projectile's surface. These engines, by providing ridges in the projectile's walls which are at an angle with respect to the line of flight through the gun, form channels or nozzles for the passage of some of the forwardly moving powder gases relative to the projectile and cause the projectile to spin by virtue of the transverse reaction effect exerted by these escaping gases. In this way, some of the tremendous energy which is available in the propellant gases is used to spin the projectile. Since some of the gases which evolve when the ammunition is fired will course through the length of the barrel between the projectile and the wall of smooth-bored barrels, or between the projectile and the lands and grooves of rifled barrels, those gases are caused to expand through the nozzles and exert rotative force against the walls thereof.

For a better understanding of my invention the various components shown in the drawings will now be identified and their functions briefly described. The conventional gun shown is of a recoilless type (although obviously my invention need not be limited to use with such guns), of which two main examples are illustrated: the one shown in Figures 2, 3A and 4 has a barrel 8, rifled with lands 9 and grooves 10, and a rearwardly expanding chamber 11. The other, which is shown in Figs. 1 and 3, has a smooth bore barrel 8a and chamber 11a. The ammunition round is substantially the same regardless of the gun type in which it is to be used, except that in accordance with my invention its projectile may be modified in a number of different ways of which one form is represented at 12 in Figs. 1, 3 and 3A, while another is depicted at 12a in Figs. 2 and 4. The projectile has an extension 13 which rests inside a cartridge case 14. Extension 13 optionally bears a number of flight-stabilizing fins 15 (only one is shown). Propellant powder 16 surrounds the projectile extension. Although the illustrated ammunition is of a special form to which my invention obviously need not be limited, it has been selected as an example primarily because it represents a type which happens to be most effective when its projectile is given a minimum spin and, therefore, my improvements are ideally suited thereto.

The projectile is provided with a bourrelet 20 which is the largest diameter portion of the projectile and, thus, in well known manner, serves as the "riding" surface which contacts the smooth bore wall of barrel 8a or lands 9 of rifled barrel 8 in moving forwardly through the barrel. On the bourrelet, starting from its rearward end (toward the projectile's base) and continuing partially or entirely across the bourrelet, even onto the projectile's nose, are slot-like helical nozzles 22 cut by any suitable means such as by a broaching machine. The projected area of these nozzles and the angle θ (see Fig. 4) between these nozzles and the axial center-line of the projectile may be varied, depending upon the amount of projectile spin desired, the weight of the projectile to be spun, the force to be supplied by a particular propellant powder, the ballistic relationships of the projectile to the gun, etc. This angle may be determined quite readily either by calculation or empirically, as desired. Thus, the nozzles are each disposed along a line which forms an acute angle with or within an imaginary plane which is inclined with respect to the axial centerline of the projectile but which is inclined, in an opposite sense, as compared with the inclination of the imaginary planes including the gun's rifling lands with respect to the gun's axial center-line. In addition, the nozzles are terminated at their forward ends in a plane which is disposed normal to the axial center line of the projectile and they are arranged symmetrical about the center line to preserve exterior ballistic control. Optionally, the rearward por-

tion or entrance into nozzles 22 may be expanded to form reservoirs 23, as shown in Figs. 2 and 4.

The operation of my invention should, by now, be apparent. The forwardly moving gases evolved upon ignition of propellant powder 16 will, in the case where rifled gun barrels are employed, be caused by the gun's lands 9 to flow (as indicated by arrows 26 in Fig. 4) through rifling grooves 10 along a line which forms the angle α with the projectile's axial center line. Not all of the gases will thus be channeled by lands 9 and grooves 10 for some will sweep axially over the lands and approach nozzles 22 as indicated by arrow 27 in Fig. 4. The gases are thus not directionalized at first, but are given direction upon entering nozzles 22, moving as indicated by arrow 28 in Fig. 4.

The gases enter the nozzles at essentially the pressure and temperature of the main body of powder gas, then expand through the nozzles to acquire sonic velocity (approximately 3000 feet per second). The reaction on the nozzles exerted by the gas in accelerating itself to sonic velocity creates a torque which acts to rotate the projectile and effectively to decelerate slightly the projectile's forward motion in the gun barrel. The latter effect essentially may be interpreted as a result of the decreased cross-section presented by the projectile to the powder gases; i. e., there is less projectile surface area on which the gas can act, than there would be if slot-like nozzles 22 were not cut into the projectile wall.

Reservoirs 23 optionally are employed to collect larger volumes of gas than might otherwise be led to enter nozzles 22, and they serve to bring the gases to rest with respect to the shell at essentially the pressure and temperature of the main body of powder gas. It should further be understood that the reservoirs may be used in conjunction with rifled gun barrels (as shown in Figs. 2 and 4) or with smooth barrels (not shown in this connection). Similarly, the simple nozzle design shown used with a smooth barrel in Figs. 1 and 3, may also be employed with rifled barrels as in Fig. 3A.

In addition to accomplishing the principal objective of imparting spin to projectiles at a low rate of speed, the presence of such reservoirs and nozzles in the bourrelet of the projectile has been found to have a further desirable effect in minimizing and suppressing undesirable yawing or "balloting" motions of the projectile during its passage through the bore. This contributes an additional factor leading to improved accuracy of the projectile in flight. These two uses of the reservoir thus naturally supplement each other in producing accurate, stable flight exterior to the bore.

Although the foregoing description of my invention's operation principally has been stated with reference to its use with rifled gun barrels, it is to be noted that my improvements work equally well in conjunction with smooth bore gun tubes such as are shown at 8a in Figs. 1 and 3. Since nozzles 22 are cut either entirely across the bourrelet

20 (as shown in Fig. 1) or partially across the forward portion thereof from the leading or forward end of reservoirs 23 (as shown in Fig. 2), some of the powder gases traveling forwardly from cartridge case 14 must enter the nozzles. Thus, the aid of gun barrel riflings to channel the gas towards the nozzle actually is not required.

It will, therefore, be noted that by my invention an effective means has been provided for imparting a controlled, low rotative speed to projectiles fired from a rifled or smooth bore gun, and this means can be accomplished in a fast, economical manner with a minimum amount of alteration being required for otherwise conventional ammunition and none for the gun. Thus, one and the same weapon is capable of firing projectiles rotated slowly by 10 my herein described novel means, or rotated at much higher speeds by such prior art devices as mechanical engagement of rotating bands with gun barrel riflings, etc. This, of course, makes it possible for a gunner to put his weapon to dual usage—an invaluable asset in the field— 15 without requiring different guns or special modifications thereof to fire projectiles at differing rotative speeds.

My invention will likewise be recognized as extensive in its adaption and is not to be restricted to the specific forms here shown by way of illustration.

25 I claim:

In an ammunition projectile to be fired from a rifled gun barrel, means for rotating the projectile at low speeds so as to offset the normal lack of symmetry of its components, comprising, a bourrelet which is circumferentially located on the projectile and whose external diameter forms a readily slidable fit with the gun barrel's bore, shallow reservoirs cut into the wall of the bourrelet forwardly from its rear end, and slot-like nozzles cut into the bourrelet from the forward end of said reservoirs 30 across the bourrelet to the forward end thereof on a line which forms an acute angle and inclined with a line parallel to the axial center-line of the projectile, the inclination thereof being disposed in an opposite sense to the inclination of the gun's rifling with respect to the gun's 35 axial center-line, and said nozzles terminating forwardly in a plane disposed normal to said axial center-line, whereby some of the gases used to propel the projectile from the gun barrel will be initially collected in the reservoirs and then be directionalized so as to flow into and 40 through said nozzles, effecting a reaction en route so as to cause the projectile to rotate.
